MEANS FOR CONTROLLING THE COATING ROLLERS AND FOR REPLENISHING THE COATING BATH FOR STRIP GALVANIZING MACHINES

Herman J. Kalberkamp, Whitehall, Pa., assignor to Mesta Machine Company, Pittsburgh, Pa., a corporation of Pennsylvania

Application December 6, 1952, Serial No. 324,460

7 Claims. (Cl. 118—11)

1

This invention relates to galvanizing and like coating of metal strip, and more particularly to means and method of controlling the coating rollers and replenishing the coating bath.

In a galvanizing line a continuous strip of steel is passed through a furnace and thence down into a pot full of molten zinc. The strip comes up from the pot between a pair of coating rollers and thence through a cooling tower to solidify the zinc adhering to the strip. In the form of galvanizing line with which the present invention is concerned, the coating rollers are journaled between a pair of brackets mounted on opposite sides of the zinc pot and are vertically movable to raise the centers of the coating rollers to above the level of the zinc bath while the strip is moving and to lower the rollers entirely into the zinc bath when the strip stops. In a conventional line the exit end of the furnace hood extends for a relatively long way down toward the zinc pot, adjacent one side of the pot between the bracket mountings, and beneath that end of the furnace hood a motor is mounted to drive two sets of shafts extending around the pot to operate screw jacks for raising and lowering the coating rollers brackets. This blocks access to the pot on three sides and leaves only the fourth side, adjacent the portion of the strip leaving the zinc bath, accessible for replenishing the bath with additional blocks of zinc and general maintenance purposes.

In accordance with the present invention provision is made for replenishing the zinc bath by automatically operating machinery mounted on the side of the pot nearest the furnace hood, which is advantageous because the cold zinc is thus added where the heat is greatest, i. e., where the preheated strip first enters the bath. In order to avoid interference with this automatic machinery, and yet at the same time to leave the opposite side of the pot clear for access to workmen, the conventional shafted drive arrangement is replaced by an arrangement comprising a motor on one side of the pot directly geared to move one of the pair of brackets supporting the coating rollers, a Selsyn generator adjacent and driven by said motor, and a Selsyn motor adjacent the other bracket and directly geared to operate the other bracket while receiving its power through the Selsyn generator. The electrical connections between the Selsyn generator on one side of the pot and the Selsyn motor on the other side of the pot are readily concealed to allow access to the pot by workmen, and the Selsyn connections synchronize the movement of

2

the brackets so that the coating rollers remain in correct horizontal alignment as they are raised and lowered.

Other objects, advantages and details of the invention will become apparent from the following detailed description and in the accompanying drawings, in which I have shown for purposes of illustration only, a present preferred embodiment of my invention. In the drawings:

Figure 1 is a partially sectioned and broken-away view of a portion of a galvanizing line embodying the invention;

Figure 2 is a plan view corresponding to Figure 1;

Figure 3 is a section taken on the line III—III in Figure 4, in the scale of Figure 4;

Figure 4 is an enlarged top plan view of the zinc pot and associated structure shown in Figure 1, with details not shown in Figure 1 and with the zinc replenishing means omitted; and

Figure 5 is a partial section taken on the line V—V in Figure 3.

Referring now in more detail to the drawings, there is provided a galvanizing line, one section of which includes a furnace with a hood 10 for heating a continuous length of steel strip 11 which passes out of the furnace around a guide roller 12 and down through an exit section 13 of the hood to a sinker roller 14, and thence vertically up between a pair of coating rollers 15 and 16 to a guide roller 17 at the top of a cooling tower. The coating rollers 15 and 16 have parallel horizontal axes in the same horizontal plane on opposite sides of the strip 11, and operate to squeeze excess molten zinc from the strip 11 as it leaves the upper surface 18 (Figure 1) of a molten zinc bath 19 in a heated pot 20.

The sinker roller 14 is journaled between a pair of brackets 21 (Figure 3) rigidly suspended beneath a beam 22 extending across the pot 20 transversely of the direction of movement of the strip 11. The beam 22 is vertically slideable between a pair of pillars 23, and a pair of hand-wheels 24 operate screw jacks (not shown) to adjust the vertical position of the beam 22, brackets 21 and sinker roller 14.

The coating roller 15 is journaled between a pair of brackets rigidly suspended beneath a beam 26 and the coating roller 16 is journaled between a like pair of brackets 27 rigidly suspended between a like beam 28. A pair of knives 29 are also suspended beneath the respective beams 26 and 28 to scrape the respective coating rollers 15 and 16. The beams 26 and 28 are

secured at one end (the left in Figure 3) to a vertically movable member 30 which is in the general form of an inverted U and has oppositely projecting vertical flanges 31 along the outer sides of its legs 30a. The flanges 31 are retained by and slideable along a pair of vertical channels 32 in a fixed frame structure 33. The member 30 rests on a nut 34 nonrotatably received in a cavity formed underneath the central portion of the member 30, and the threaded upper end of a vertical shaft 35 is screwed through the nut 34 to jack the member 30 up and down. The lower end of the shaft 35 is journaled in the fixed structure 33 and is keyed to a worm wheel 36 driven by a worm 37 keyed on a shaft 38 driven by a reversible electric motor 40. The motor 40 is connected to a source of power through suitable controls and is operable to rotate the shaft 35 and thus jack the adjacent ends of the beams 26 and 28 up and down simultaneously.

The other ends of the beams 26 and 28 (to the right in Figure 3) are jacked up and down through identical mechanical connections by a Selsyn motor 41. A corresponding Selsyn generator 42 is driven directly by the rear end of the drive shaft of the motor 40, and powers the motor 41 through five transmission lines carried in a buried conduit 43 extending around the pot 20 (as indicated diagrammatically in Figure 4). The operating characteristic of the generator 42 is to drive the motor 41 at exactly the same rate and in the same direction as the motor 40, so that when the motor 40 raises and lowers the end of the beams 26 and 28 adjacent to it the Selsyn motor 41 simultaneously raises and lowers the other ends of these beams to exactly the same extent. The coating rollers 15 and 16 are thus kept in horizontal alignment in their raised and lowered positions. When the strip 11 is moving regularly through the bath the coating rollers 15 and 16 are disposed with their centers at about the level of the bath, the exact level being adjustable through the motors 40 and 41 to control the coating weight. Whenever the strip is stopped for any reason the motor 40 is immediately operated to lower the rollers 15 and 16 below the surface of the bath in order to prevent the zinc from solidifying on the rollers while waiting for the strip 11 to resume its regular movement.

The motors 40 and 41 and generator 42 are mounted on opposite sides of the pot 20 and do not obstruct entry to the other two sides of the pot. The coating rollers 15 and 16 are mounted relatively close to the exit side of the pot, in terms of the general line of movement of the strip 11, in order to increase the clearance between the exit section 13 of the furnace hood and the entry side of the pot therebeneath. A receiver member 44 is mounted against the entry side of the pot, with an open top above the bath to receive blocks of zinc to replenish the bath 19, with submerged openings 45 in the bottom to allow the melted blocks to flow into the bath (Figures 1 and 2). This arrangement is advantageous because it introduces the relatively cold blocks of zinc close to the place where the pre-heated strip 11 enters the bath, thereby melting the blocks relatively quickly. Moreover, the blocks are introduced relatively far from the place where the strip leaves the bath, thereby minimizing fluctuations of temperature of the coated strip passing to the coating rollers 15 and 16. The upper end of the replenishing member 44 receives blocks of zinc 46 from an inclined

roller conveyor 47 extending in the general direction of movement of the strip 11. A second inclined roller conveyor 48 discharges onto the conveyor 47, and in turn receives zinc from a third inclined roller conveyor 49 fed by a belt conveyor 50 driven by a motor 51 for depositing zinc blocks at a controlled rate onto the roller conveyor 49, from which the blocks roll freely into the receiver 44. The belt 50 is positioned to one side of the line of movement of the strip 11, and extends generally parallel to it for a considerable distance so that a row of spaced zinc blocks can be placed at one time along the length of the belt 50 and thereafter the motor 51 operates the belt 50 to send the blocks one after the other into the bath at a predetermined rate, such as one about every three minutes. The motor 51 can be operated at a very slow continuous rate with electrical control connections to the drive means for the strip 11 in order to synchronize the rate of replenishment directly with the speed of movement of the strip 11. However, the speed of movement of the strip is not the sole factor governing the rate of replenishment of the zinc bath, and it is preferable to operate the belt intermittently under control of an electric time clock 52 which is adjustable to control the periods between operation of the motor 51 in such manner as to coordinate the automatic replenishment with the current operation of the galvanizing line. The motor 51 is also preferably interconnected by automatic electric controls with the power system for moving the strip 11 so that when the strip 11 stops the motor 51 is inactivated until the strip resumes movement. This is preferably accomplished by connecting the timer 52 in parallel with the drive motor 53 which operates the pinch rolls 54 pulling the strip 11 through the line. In this way the motor controller 55 cuts out the current to the motor 51 at the same time it cuts out the pinch roll motor 53. With such automatic replenishing system the task of supervising and replenishing the bath requires less time and attention and is performed with greater ease and regularity. Moreover, the exit side of the pot 20 is unobstructed by the drive means for raising and lowering the coating rollers, or by the means for supplying zinc to the bath, and this makes the pot 20 readily accessible for supervising the galvanizing operation and maintaining the galvanizing equipment.

While I have illustrated and described a present preferred embodiment of the invention and method of practicing the same, it will be understood that the invention may be otherwise variously embodied and practiced within the scope of the following claims.

I claim:

1. A galvanizing or like line comprising a pot for a bath of molten coating metal, a furnace hood with a terminal portion extending above and across one side of the pot and down toward a central portion of the pot, means to pass a metal strip through the furnace hood into the pot and thence up out of the pot, a pair of coating rollers disposed on opposite sides of the path of the strip emerging from the pot, supporting means from which the coating rollers are suspended extending above and across the pot transverse of the line of movement of the strip, separate jacking means adjacent the opposite ends of said supporting means to raise and lower said ends, a pair of motors adjacent and mechanically connected to operate the respective jacking means, a Selsyn generator adjacent and mechan-

ically driven by one of said motors, and the other of said motors being a Selsyn motor electrically connected to the Selsyn generator and thereby driven in synchronized relation with said one motor, whereby said one motor is operable to raise and lower the coating rollers while maintaining their alignment with each other and the strip.

2. A galvanizing or like line comprising a pot for a bath of molten coating metal, a furnace hood with a terminal portion extending above and across one side of the pot and down toward a central portion of the pot, means to pass a metal strip through the furnace hood into the pot and thence up out of the pot, a pair of coating rollers disposed on opposite sides of the path of the strip emerging from the pot, supporting means from which the coating rollers are suspended extending above and across the pot transverse of the line of movement of the strip, separate jacking means adjacent the opposite ends of said supporting means to raise and lower said ends, a pair of motors adjacent and mechanically connected to operate the respective jacking means, a Selsyn generator adjacent and mechanically driven by one of said motors, the other of said motors being a Selsyn motor electrically connected to the Selsyn generator and thereby driven in synchronized relation with said one motor, whereby said one motor is operable to raise and lower the coating rollers while maintaining their alignment with each other and the strip, and a conveyor for pieces of cold coating metal to be added to the bath, said conveyor being mounted adjacent said one side of the pot beneath the terminal portion of the furnace hood.

3. A galvanizing or like line comprising a pot for a bath of molten coating metal, a furnace hood with a terminal portion extending above and across one side of the pot and down toward a central portion of the pot, means to pass a metal strip through the furnace hood into the pot and thence up out of the pot, a receiver member mounted in the pot adjacent said one side, said receiver member having an open top and a perforated lower portion, and conveyor means for feeding pieces of cold coating metal into the upper end of the receiver member.

4. A galvanizing or like line comprising a pot for a bath of molten coating metal, a furnace hood with a terminal portion extending above and across one side of the pot and down toward a central portion of the pot, means to pass a metal strip through the furnace hood into the pot and thence up out of the pot, an elongated inclined motor-driven conveyor belt mounted in spaced relation from one side of the pot and adapted to support and elevate pieces of cold coating metal to be added to the pot, and roller conveyor means descending from the raised end of the conveyor belt to said one side of the pot to discharge said pieces into the pot, whereby the bath is replenished when necessary through operation of the belt.

5. A galvanizing or like line comprising a pot for a bath of molten coating metal, a furnace hood with a terminal portion extending above and across one side of the pot and down toward

a central portion of the pot, means to pass a metal strip through the furnace into the pot and thence up out of the pot, a conveyor belt having an upper reach extending generally horizontally and adapted to support pieces of cold coating metal to be added to the pot, a motor connected to move the belt to discharge said pieces, means to convey the discharged pieces into the pot, and timing means controlling said motor to synchronize the rate of discharge of said pieces into the bath with the rate of withdrawal of the coating metal from the bath.

6. A galvanizing or like line comprising a pot for a bath of molten coating metal, a furnace hood with a terminal portion extending above and across one side of the pot and down toward a central portion of the pot, means to pass a metal strip through the furnace into the pot and thence up out of the pot, a conveyor belt having an upper reach extending generally horizontally and adapted to support pieces of cold coating metal to be added to the pot, a motor connected to move the belt to discharge said pieces, means to convey the discharged pieces into the pot, and control means to stop the belt motor when the metal strip stops moving.

7. A galvanizing or like line comprising a pot for a bath of molten coating metal, a furnace hood with a terminal portion extending above and across one side of the pot and down toward a central portion of the pot, means to pass a metal strip through the furnace hood into the pot and thence up out of the pot, a pair of coating rollers disposed on opposite sides of the path of the strip emerging from the pot, supporting means from which the coating rollers are suspended extending above and across the pot transverse of the general line of movement of the strip, separate jacking means adjacent the opposite ends of said supporting means to raise and lower said ends, a pair of motors mechanically connected to operate the respective jacking means, a Selsyn generator adjacent and mechanically driven by one of said motors, the other of said motors being a Selsyn motor electrically connected to the Selsyn generator and thereby driven in synchronized relation with said motor, a receiver member with an open top and a perforated lower portion mounted in the pot adjacent said one side of the pot, a series of descending roller conveyors having a final section disposed beneath said furnace hood terminal portion to discharge into the open top of the receiver member, and a motor-driven inclined conveyor belt for discharging pieces of cold coating metal onto the upper end of the series of roller conveyors, said belt extending generally parallel to the general line of movement of the strip in offset relation to one of said opposite sides of the pot.
